Inventor

By his Attorney *Joseph Elder*
Phil. T. Dodge

UNITED STATES PATENT OFFICE.

JOSEPH ELDER, OF PEORIA, ILLINOIS.

CARBURETOR.

SPECIFICATION forming part of Letters Patent No. 409,570, dated August 20, 1889.

Application filed April 12, 1889. Serial No. 307,065. (No model.)

To all whom it may concern:

Be it known that I, JOSEPH ELDER, of Peoria, in the county of Peoria and State of Illinois, have invented certain Improvements 5 in Carburetors, of which the following is a specification.

This invention relates to an apparatus for carbureting air or gas for illuminating and heating purposes; and it consists in a body 10 provided with peculiarly-arranged chambers to contain a hydrocarbon oil and secure the contact of the air or gas therewith.

In the accompanying drawings, Figure 1 is a longitudinal vertical section of my carburetor. 15 Figs. 2 and 3 are sections of the same on the line *x x*, looking in opposite directions.

Referring to the drawings, A represents a closed casing, of sheet metal or other suitable material, preferably of an oblong rectangular 20 form. This body is divided by the horizontal partitions *a* and *a'* into three chambers *b*, *c*, and *d*. An inlet-pipe *e* leads downward through the top of the body directly into the bottom chamber *d*, where it terminates at the 25 top of the chamber in a cross-pipe *e'*, having a narrow slit or orifice. At the opposite end of the casing a pipe *g* leads from the top of the bottom chamber *d* upward to the top of the chamber *c*. This pipe terminates at each 30 end in a cross-pipe having a narrow slit therein. At the opposite end from the pipe *g* a pipe *h*, having a slotted cross-arm in the top of chamber *c*, leads into the top chamber *b*. This top chamber is provided at the 35 opposite end with an outlet-pipe *i*. The chambers *c* and *d* are provided at one end with filling-spouts *f*.

In operating the apparatus the lower two 40 chambers are filled with naphtha or similar material to a point near the lower ends of the respective pipes. The air or gas entering the pipe *e* descends into the bottom chamber *d*, and is distributed and delivered into the top of this chamber in a thin sheet or film above 45 the surface of the naphtha, over which it flows to the opposite end of the chamber, where it ascends through the pipe *g* into the top of the chamber *c*, where it is again diffused or distributed and compelled to pass 50 over the surface of the naphtha to the pipe *h* at the opposite end, where it ascends into

the chamber *b*, and passing therethrough escapes at *i*. The top chamber *b* may be filled with cotton or other absorbent material to prevent excessive saturation of the gas or air. 55 The air or gas charged with the hydrocarbon vapor is heavier than air and naturally sinks. Owing to this fact it is advantageous to deliver the air and gas into the bottom chamber first and to compel their ascent through the 60 chambers above. Being delivered under pressure, the air or gas has considerable velocity and travels across the upper part of the chambers from the inlet to the outlet openings with considerable rapidity. 65

The delivery of the air or gas first into the base of the apparatus and thence upward toward the point of delivery is advantageous, in that the air is thus retarded sufficiently to secure a thorough combination with the 70 hydrocarbon vapor, while at the same time any excess of vapor which may be momentarily suspended in the air is precipitated within the apparatus instead of being carried over into the delivery pipe. 75

Having thus described my invention, what I claim is—

1. In a carburetor, the body divided by horizontal partitions into distinct chambers, in combination with the pipe leading into the 8c top of the bottom chamber, the pipe leading from the top of the bottom chamber to the top of the one above and the outlet-pipe *i*, each of said pipes terminating in a cross-pipe with a narrow horizontal slit therein, 85 substantially as described and shown.

2. In a carburetor, a chamber *d* nearly filled with a hydrocarbon, in combination with an inlet-pipe presenting a narrow slit across one end of the chamber above the 90 liquid, and a similar slotted outlet-pipe at the opposite end of the chamber, whereby air or gas is directed in a thin sheet across the top of the chamber.

In testimony whereof I hereunto set my 95 hand, this 9th day of March, 1889, in the presence of two attesting witnesses.

JOSEPH ELDER.
